Attorney

UNITED STATES PATENT OFFICE.

JOHN GIZEWSKI, OF DENVER, COLORADO, ASSIGNOR OF ONE-HALF TO JOSEPH J. KLIMOSKI, OF DENVER, COLORADO.

HEADLIGHT-CONTROL SWITCH.

Application filed February 16, 1924. Serial No. 693,304.

This invention relates to a headlight control switch and to the manner of connecting the same in a headlight circuit of an automobile.

5 An important object of the invention is to provide a foot-operated dimmer switch so connected with the usual dimmer switch applied to vehicles that the headlights of the vehicle may be temporarily dimmed by 10 operation of this switch when the ordinary headlight switch is positioned so that the headlights would be bright.

15 A further object of the invention is to provide a device of this character and so connect the same that the operation of the headlights is not affected if the normal headlight switch is positioned for dim lighting of the headlights.

20 A still further object of the invention is to provide a switch for this purpose which may be very readily and cheaply produced, which is simple in its construction and operation and which will be a general improvement in the art.

25 These and other objects I attain by the construction shown in the accompanying drawings, wherein, for the purpose of illustration is shown a preferred embodiment of my invention and wherein:

30 Figure 1 is a vertical sectional view through a switch constructed in accordance with my invention showing the same in the bright position;

35 Figure 2 is a similar view showing the same in the dim position;

Figure 3 is a section on the line 3—3 of Figure 2;

Figure 4 is a diagrammatic view, both switches being shown in the dim position.

40 Referring now more particularly to the drawings, the numeral 10 indicates a casing having a top plate 11 formed to provide overhanging flanges 12 the purpose of which will hereinafter appear. Through this top plate an aperture is formed, as at 13, through 45 which extends the reduced stem 14 of a plunger 15, the juncture of the reduced stem with the plunger providing a shoulder 16 which when it comes into engagement with the top plate 11 limits the movement of the plunger in this direction. The upper end of the extension is preferably provided with an engagement plate 17 adapted for contact by the foot, this plate being held in position

by a securing element 18 engaged with the 55 extension.

Opposed side walls of the casing 11 have mounted thereon insulation 19 disposed upon the interior face of the walls and the walls are provided at spaced intervals with aligned 60 pairs of openings 20 and 21. The insulation 19 is provided in alignment with these openings upon its inner surface with contact elements 22, connectors 23 extending through the insulation and providing a common 65 means for attaching the contacts 22 and for electrically connecting lead wires 24 to these contacts, the lead wires extending through openings 20 or 21 as the case may be.

Each contact 22 consists of a substantially 70 U-shaped member having the ends of the arms 25 thereof bent inwardly to engage against the plunger 15, this plunger being preferably circular in cross section. The arms 25 are of spring metal so that they 75 bring a constant pressure to bear upon the plunger and insure a proper contact with the plunger. The plunger 15 consists of insulating material and is provided at spaced intervals with a pair of insulating bands 80 26 and 27 which completely encircle the plunger and are adapted for coaction with pairs of contacts aligned with the openings 20 or 21 respectively. The contact band 26 is so spaced from the shoulder 16 that when 85 the shoulder is engaged with the cover plate 11 this band connects the contacts 22 aligned with the openings 20 completing a circuit therebetween. The lower end of the plunger is provided with a reduced extension 28 about 90 which is disposed an insulating washer 29. The opposed lower end of the casing has seated thereon an insulating plate 30 and between the washer 29 and plate 30 a spring 31 is disposed which normally maintains the 95 plunger with the shoulder 16 in engagement with the plate 11. The reduced extension 28 of the plunger serves to limit the downward movement of the plunger when the band 27 comes into alignment with the contacts 22 which are aligned with the openings 21 so that when this plunger is depressed to its fullest extent these contacts are electrically connected.

In the use of the device the foot boards F 105 of the vehicle are preferably provided with an opening through which the casing 10 may be extended until the plate 11 comes into

engagement with the upper surface thereof. Securing elements are then directed through the openings of the flange of the plate 11 to secure the casing in position.

5 Referring now more particularly to the drawings in Figure 4 of which I have disclosed a circuit including a switch constructed in accordance with my invention and in which the battery is designated by B, 10 the headlights by H, and the ordinary lighting switch by S. The blade of the switch S coacts with contacts C¹ and C² which are in turn connected with binding posts P¹ and P². In the circuit illustrated the lighting 15 system is that in which in one position of the switch a resistance is inserted in the circuit to restrict the amount of current passing through the illuminating elements of the headlights H, this resistance being indicated at R and connecting the binding post P² with the contact C² of the switch S. The binding post P¹ is directly connected with the post C¹. Thus when the switch is engaged 20 with the contact C¹ there is no resistance in the circuit and the circuit is to the binding post P¹. When the switch is positioned with the contact C² the resistance is in the circuit and the circuit is to the binding post P². This binding post P² is connected by a 25 wire 32 with a wire 33 connecting similar contacts of the illuminating elements of the headlights, the opposite contacts thereof being grounded. The contact P¹ is connected by a wire 34 with one binding post each of 30 the upper and lower pairs of binding posts as indicated. The other binding post of the upper pair is connected by a wire 35 with the wire 33. The other binding post of the lower pair is connected by a wire 36 with 35 the contact C². The operation of the circuit just described is as follows: Assuming the switch S to be engaged with the contact C¹ and the foot-operated dimmer switch, generally indicated at D, to be in its normal 40 or elevated position and the circuit is as follows: the battery at one side to the ground, the opposite side of the battery to the switch, to contact C¹, binding post P¹, wire 34, contact 22 of the upper pair, band 45 26, a second contact 22, wire 35 to the wire 33 and through the headlights to the ground. If the switch D is now changed in its position and moved to the lower position as by 50 pressing the foot thereon, the circuit is altered as follows: from the binding post P¹ to a contact 22 of the lower pair, band 27, a second contact of the lower pair, wire 36, contact C², resistance R, binding post P², wire 32 and wire 33 to headlights and 55 ground.

It will, therefore, be seen that with the headlight switch S in the bright position the switch D is operative to change the selection of the switch S from bright to dim.

60 With the switch engaged with the contact

C² there is no flow of current from the switch S to the switch D and accordingly this switch is inoperative to effect a change in selection. If the switch D is in the bright or elevated position, it will be seen that the switch S is 70 effective to effect a change of selection by the switch D. The circuit with the switch S in connection with the contact C¹ being given above, this forming the bright light circuit and if the switch is associated with 75 the contact C², as hereinbefore stated, no current is fed to the switch D¹ and the circuit is accordingly through the resistance R, wire 32, wire 33 to the ground. If the switch D be in the lowered position so that 80 the band 27 connects its associated contacts, then the switch S is inoperative to effect a change of selection for the reason that regardless of the position of the switch S the circuit is always through the resistance R. 85 It will, therefore, be seen that in effect a lighting circuit is produced having therein two switches each having a bright and a dim position, each switch being effective to change the selection of the other switch while 90 the other switch is in the bright position and ineffective to change the selection of the other switch while this other switch is in the dim position.

The advantage of this arrangement will 95 be obvious to all who drive automobiles having dimmer switches thereon. It is fairly a common occurrence that a driver having his lights already dimmed and meeting someone with already bright lights inadvertently changes the position of his switch when the other operator changes from his bright lights to his dim lights, the first operator being under the impression that his lights were brightly illuminated. This mistake is a frequent occurrence and often results in disastrous dazzling of passing drivers. With the construction shown this is impossible for it is only necessary that one of the switches be in the dim position and 100 the circuit will remain dimmed regardless of manipulation of the second switch. At the same time a device is provided which is readily manipulated by the foot to give a temporary dimming of the lights while running under bright lights and a device which may be very readily applied to the vehicle. While the illustrated structure of the switch D is preferred it will, of course, be obvious 105 that this structure is capable of modification and it will likewise be obvious that the circuit illustrated only shows the switches in use in one form of lighting circuit and that these switches are capable of similar use in other forms of circuits. This being 110 115 120 125 the case I do not limit myself to the specific structure or arrangement hereinbefore set forth except as hereinafter claimed.

I claim:

130 In a foot operated dimmer switch, a cas-

ing having an opening formed in one end wall thereof, a plunger within the casing and having its ends reduced, one of said reduced ends extending through the opening of the wall for engagement by the foot, the corresponding end of the plunger abutting said end wall to limit movement of the plunger in one direction, the other of said extensions engaging the opposite end wall of the casing
10 to limit movement of the plunger in the opposite direction, a spring surrounding the last named reduced end of the plunger and extending between the last named end wall of the casing and the adjacent end of the plunger, insulating panels within the casing at opposite sides of the plunger, said plung-

er being of insulating material and spaced bands of conducting material surrounding the plunger, one of said bands being operative to connect one of said pairs of contacts when the plunger is at the first named limit of its movement, the other of said bands connecting the other of the pairs of contacts when the plunger is at the last named limit of its movement, spaced pairs of opposed contacts carried by said panels and embodying terminal portions partially embracing the plunger to form guides therefor.

In testimony whereof I hereunto affix my ²⁰ signature.

JOHN GIZEWSKI.
